UNITED STATES PATENT OFFICE.

EDWARD WELLS BEACH, OF WATERBURY, CONNECTICUT.

FOUNDRY-RIDDLE.

1,078,532.

Specification of Letters Patent. Patented Nov. 11, 1913.

Application filed August 14, 1913. Serial No. 784,660.

To all whom it may concern:

Be it known that I, EDWARD W. BEACH, a citizen of the United States, residing at Waterbury, in the county of New Haven, 5 State of Connecticut, and whose post-office address is P. O. Box 1016, (or 133 West Main street,) Waterbury, Connecticut, have invented certain new and useful Improvements in Foundry-Riddles; and I do hereby 10 declare the following to be a full, clear, and exact description of the invention, such as will enable others skilled in the art to which it appertains to make and use the same.

15 The invention relates to foundry riddles which are employed to riddle the sand used in the making of molds.

Foundry riddles are subjected to extremely rough usage and their development 20 in structure to withstand rough treatment led to the universally used wooden rim riddle of the present. To fulfil the requirements it was necessary to employ selected wood in the manufacture of the riddles and 25 the increasing scarcity of suitable material has led many to seek a substitute in an all metal riddle. The procedure usually adopted for substituting metal for wood in the manufacture of various articles did not, in 30 this case, meet with success in view of the peculiar requirements of strength rigidity and lig:thness which a foundry riddle must possess to be commercially practicable, while the present invention provides structural characteristics which make possible 35 the attainment of the object in a most satisfactory manner.

An all metal foundry riddle, in order to be commercially practical, must be as light 40 as the wooden prototype, have the mesh strongly secured in the wall, be provided with a projecting edge below the mesh which edge can withstand severe rapping without loosening the mesh, and provide a broad 45 hand hold for the operator, and have a wall sufficiently resilient and proof against twisting 50 to withstand the abuse commonly given to riddles of this class, such for instance its use standing on edge by the molder as a 55 seat during the luncheon hour.

While the abuse just cited would seem to be uncalled for and unnecessarily without the range of requirements for a riddle, such abuse has become customary in foundries 60 and only those riddles which can success-

fully withstand this abuse are available as a commercial article of the kind today.

The present invention comprehends a structure especially designed to fulfil the exigencies of utility and abuse met in foundry practice, the production of a serviceable all metal foundry riddle.

I have illustrated in the accompanying drawing, a riddle embodying the structural characteristics comprising the invention as 65 hereinafter described and claimed, and in the drawing—

Figure 1, is a side elevation of the finished riddle partly in section and Figs. 2, 3, 4, 5, and 6 are vertical sections through the wall 70 and mesh at successive stages in the formation of the article shown in Fig. 1.

Referring to the drawing: The wall A of the riddle is preferably formed as an annulus from a piece of flat metal, the ends 75 of which are united by welding or by a riveted lap joint, the welded joint being preferable and incapable of indication upon the drawing. The wall piece A is first rolled with a V-shaped channel B (see Fig. 2) into 80 which channel the edge of a mesh disk C is inserted, when the V-shaped channel B is closed tightly upon the mesh C as shown in Fig. 3, forming the lap D. The lap D is then folded downwardly (see Fig. 4) 85 while the inner surfaces of the wall A below and above the mesh are maintained in alignment, which draws the mesh disk taut, the lap D finally reaching the position shown 90 in Fig. 5 lying tightly against that portion of the wall A below the mesh disk. The lowermost portion of the wall A is then bent outwardly into a flange E (see Fig. 5) which is then lapped around a wire ring F (see 95 Figs. 1, 5 and 6) placed upon and fitting the outside of the turned down lap D (see Fig. 6). It will be noted now that the flange E in Fig. 6 provides a wide hand hold with rounded edges, a necessary feature of the device. It will also be noted that the structure of the completed projecting wall below the mesh is extremely strong and that blows upon the flange E (see Fig. 6) will not 100 loosen the mesh but tend to tighten the lap D and the mesh contained therein.

The upper edge of the wall A is turned outwardly over a ring G similar to but smaller than the ring F and the wall A above the mesh C is provided with stiffening corrugations H running at an angle to 110

the axis of the cylindrical wall A. Running as they do, at an angle to the axis of the wall A, the corrugations have curvatures in two directions which afford the required resistance to the twisting of the wall. I preferably use the corrugations in a truss formation, such for instance as that shown, which greatly increases the wall A's capacity to resist twist when made of the light weight thin metal necessarily employed to provide the proper weight riddle. The truss corrugation of the wall A above the mesh coöperates with the stiff trebled wall below the mesh to afford the stiff abuse-withstanding structure required for foundry practice and usages.

Cross-wires J for supporting the mesh disk C are passed through apertures in the wall and their ends bent to hold them in position.

The metallic riddle made as illustrated in the drawing and as hereinbefore described possesses all of the advantageous characteristics of the wood rim riddle and can be made even stronger and more durable than the wood rim riddle inside the permissible weight. Without the truss-form corrugations in the part of the wall above the mesh disk this wall will not be sufficiently rigid if the metal is thin enough to keep the riddle within the permissible weight, and the structure as a whole will bend and twist and will not fill the requirements of a commercial article. The described form of the wall below the mesh disk is adapted to withstand extreme abuse and the structure as a whole presents a most perfect commercial article.

What I claim is:—

1. In a foundry riddle, a mesh disk, a sheet metal wall having an outwardly and downwardly bent fold gripping the edge of said mesh disk, a ring surrounding said downwardly bent fold, the said wall being bent under the lower edge of said fold and

curled upon said ring to provide a wide and smooth hand hold and to prevent the loosening of said fold, substantially as described.

2. In a foundry riddle, a mesh disk, a sheet metal wall having an outwardly and downwardly bent fold gripping the edge of said mesh disk, the said wall being bent under the lower edge of said fold to provide a wide and smooth hand hold, substantially as described.

3. In a foundry riddle, a mesh disk, and a sheet metal wall having an outwardly and downwardly bent fold gripping the edge of said mesh disk, the lower edge of said wall being turned about the lower edge of said fold to retain the same, substantially as described.

4. In a foundry riddle, a mesh disk, a sheet metal wall having an outwardly and downwardly bent fold about the lower edge of which the lower edge of the said wall is turned, the said wall above said mesh disk being provided with truss forming corrugations imparting to the upper portion of said wall a stiffness corresponding to the stiffness of the folded lower projecting part, substantially as described.

5. In a foundry riddle, the combination with a mesh disk of a cylindrical sheet metal supporting wall therefor having corrugations inclined to its axis, substantially as described.

6. In a foundry riddle, the combination with a mesh disk of a cylindrical sheet metal supporting wall therefor having corrugations arranged to form a truss structure, substantially as described.

In testimony whereof I affix my signature, in presence of two witnesses.

EDWARD WELLS BEACH.
